Design of a
Clock Case.

Dec. 1124

Joseph A. Munn, of New York, N.Y.
Letters Patent No. 1124. Dated July 26, 1859.

The Schedule referred to in these Letters Patent, and marking part of the same.

To all whom it may concern:

Be it known that I, Joseph A. Munn, of the City, County and State of New York, have produced a new and original design for Clock Bases, and I do hereby declare that the following is a full and exact description thereof, reference being had to the accompanying drawings, of which

Fig. 1. is a front elevation.

Fig. 2. is a plan, in section, at the base.

The general outline of form at the base is that of three sides of an octagon, as shown at a, Fig. 2. and this general outline is retained throughout;

The lower part (a), is a pedestal, having a circular opening (b) in its front, on either side of which is a panel, circular with preference to the inner edge and straight on the other edges, containing ornamentation in the form of a Sprig of Oak with leaves and acorns; On either side of these are the retreating angles before referred to.

It has also a plain projecting base (a) and cap (c). Above the pedestal is the body of the case (c), which has on either side a pilaster (d, d) projecting slightly from its surface; these have a base composed of a small half bead below, cavetto and bead above and the body of which is configured as shown in the drawings.

Each pilaster has half of its breadth upon the front angle of the case, the other half recedes upon the side, retreating angles,

A cap or cornice (c) surmounts the whole. It consists of an ogee and bead and extends from side to side, but its line is broken by an arch in the center through which is carried the same molding and this also has the octagonal form just mentioned; At the back (e) is a thin projecting margin extending up and down the sides, with a configured outline, not materially differing from that given to the case; The opening (h) is for receiving the dial, which with the movement &c are matters well understood.

Des. 1124

Having thus described my improved design, what I claim therein as new and desire to secure by letters Patent is...

The general design and configuration herein described.
